DETACHABLE DOORLOCK

John H. Shaw, New Haven, Conn., assignor to
Sargent & Company, New Haven, Conn.

Application May 17, 1928, Serial No. 278,544

39 Claims.

(Cl. 70—91)

My invention relates to detachable door locks, and more especially to such locks in which the detachment of the lock is effected or controlled by the use of a key or keys.

5 It is highly desirable in certain instances to provide locks in which the locking mechanism may be readily withdrawn in order to change the combination thereof, and for other purposes, and to this end it has been proposed to provide 10 a secondary locking system, particularly in cylinder locks, the secondary locking system controlling the detachment of the lock mechanism and being in turn controlled by the operation of a key. In the prior locks of this character, each 15 pin tumbler of the locking mechanism has been provided with a plurality of breaks, one set of breaks being brought into alignment when the lock is operated normally in retracting a latch bolt or the like, and another set which is brought 20 into alignment to permit the operation of the secondary lock and the detachment of the locking mechanism from its case. A special key is provided in each instance for controlling the operation of the secondary locking system. The present 25 invention relates in general to locks of this type, and has for its primary object a lock which is of simple construction and less apt to get out of order than those previously proposed or in use.

Another object of the invention is to provide 30 a lock mechanism of the above type which is provided with pin tumblers or the like in which but a single set of breaks is necessary.

Still another object of the invention is to provide a lock mechanism which may be readily withdrawn from a lock case without the use of tools and in which the detachment of the lock mechanism is under the control of a key inserted 35 into the same opening in which the key used for the normal operation of the lock is received.

40 Still another object of the invention is to provide a lock of the above type in which there are no exposed or accessible portions of the locking mechanism which may be tampered with by one seeking to force the lock, and in which the parts 45 of the secondary locking system are entirely carried within the lock case, and only accessible upon the use of a proper key.

In a more specific aspect, the invention contemplates a lock having the above characteristics 50 which is suitable for use in that form of locking mechanism for a door or the like, in which a portion of the lock mechanism, for instance the pin tumbler mechanism, is carried in the handle of the door and is provided with an extension 55 passing into the main body of the lock, which

may be mortised into the door or secured in any other manner upon the same.

A further object of the invention is to provide a lock mechanism of the latter type in which the door handle and lock mechanism may be detached as a unit from the door or such other part to which it may be attached. 5

To these and other ends, the invention consists in the novel features and combination of parts to be hereinafter described and claimed. 10

In the drawings,

Fig. 1 is a view showing a portion of a door having a lock in accordance with my invention used in connection therewith;

Fig. 2 is a sectional view along line 2—2 of Fig. 1; 15

Fig. 3 is a sectional view along line 3—3 of Fig. 1, but on an enlarged scale;

Fig. 4 is a sectional view along line 4—4 of Fig. 2, but on enlarged scale; 20

Fig. 5 is a sectional view along line 5—5 of Fig. 3, but on an enlarged scale;

Fig. 6 is a sectional view similar to Fig. 5, but showing certain parts of the locking mechanism in a different position; 25

Fig. 7 is a sectional view along line 7—7 of Fig. 6; and

Fig. 8 is a sectional view along line 8—8 of Fig. 3. 30

I will now describe my invention in connection with the preferred embodiment thereof shown in the drawings, wherein my improved form of detachable door lock is shown in the form of a cylinder lock carried in the handle of a door, although it will be understood as the description of the invention proceeds that in certain aspects the invention is not limited to use in the handle of a door or the like, but may be used in other and different relations. 35

Referring then to the drawings, the reference 40 numeral 9 indicates in general a door having mortised therein a lock case 10 provided with a pivoted latch bolt 11, to which is connected a stem 12, provided at an inner end with laterally projecting parts 13 and 14 having thereon lugs 15 and 16 which may be engaged by rollbacks 17, 18 and 19, in a manner to be pointed out hereinafter, to retract the latch bolt 11, while the latter is normally urged into protracted position by compression spring 20 received on and surrounding 45 stem 12, one end of spring 20 being in contact with latch 11 and the opposite end in contact with a transverse part 21 of lock case 10. 50

On either side of door 9 are escutcheon plates 55 22 and 23 in which are mounted, preferably in

the permanent manner, collars 24 and 25 having tightly received therein a tubular element 26 which is secured against rotation in and extends through the lock case 10 and outwardly through collars 24 and 25. Received within element 26 at one end thereof is a shank 27 of knob 28, while in the opposite end of tube 26 is a shank 29 of knob 30, shank 29 being provided with slots 31 and 32 in its inner end for the reception of talons 33 and 34 of rollback 17, while shank 27 of knob 28 is provided on its inner end with similar slots for the reception of the talons on rollback 19. Shank 27 is held against movement in an axial direction by means of key 26^a supported in case 10 and extending into groove 27^a in shank 27, while a similar key is received in groove 29^a in shank 29.

The shank 29 is made of two parts 35 and 36 constrained to rotate together by means of one or more tongues 37 on part 36 received within grooves 38 on part 35, while the outer end of shank 29 is provided with a disk-like flanged end 39 provided on its periphery with threads 40, received within a similar threaded portion of handle 30, handle 30 being hollow, as shown in the drawings, and having mounted therein a cylinder lock generally designated by the reference numeral 41, the cylinder lock 41 being provided with a casing 42 clamped between end 39 of shank 29 and an inner face 43 of knob 30, rotational movement of casing 42 being prevented by integrally formed lugs 30^a on case 30 which engage a suitable part of casing 42. The lock case 42 is provided with circular projections 44 and 45 received within similarly shaped openings in face 43 and end 39 of shank 29, the threads 40 providing means for adjusting the flanged end 39 against the adjacent end of casing 42 in order to secure the latter tightly in place. One or more threaded openings 46 are provided partly in handle 30 and partly in wall 39 in which are received screws 47 which prevent rotational movement of handle 30 on shank 29.

Mounted in case 42 is a key plug 48 having the usual key opening 49 and a plurality of transverse openings 50, which together with a similar number of cavities 51 in case 42, contain the pin tumbler sections 52 and springs 53. One end 54 of key plug 48 extends outwardly through a suitable opening in handle 30, while at its opposite end key plug 48 is provided with a shank 55 secured by means of pin 56 to a thimble 57 having received in a square opening therein a square rod 58 which passes through a similarly shaped opening 59 in rollback 18 and into an opening 60 in shank 27 of handle 28. The key plug 48 is secured in casing 42 against movement in an axial direction by means of clip 61 pivotally mounted on casing 42 by means of screw 62, clip 61 being provided with a pair of legs 63 and 64, which straddle the key plug 48 and are received in groove 65.

In order to dog rollback 17 against movement and thereby to prevent the latch 11 from being withdrawn by the use of handle 30, which ordinarily will be on the outside of the door, a pivoted lever 66 is provided in the outer wall 67 of lock case 10, pivoted lever 66 being connected by means of rod 68 to a locking pin 69, which is supported in a transverse part 70 of case 10, and adapted to enter openings 71 and 72 in tubular element 26 and shank 29, respectively, to lock these parts together and thereby prevent rotation of handle 30. In order to cover the screws 47 and to prevent tampering therewith a shroud 73 is provided

having a cylindrical portion 74 surrounding tube 26 and received between tube 26 and collar 24 and a conical section 75 which extends outwardly and axially from cylindrical portion 74 to the adjacent end of handle 30, the outer surface of conical surface 75 conforming in shape to the shape of handle 30.

The operation of the lock mechanism described above will be readily understood from the foregoing description and may be briefly described as follows: The rollbacks 17, 18 and 19 are capable of independent rotary movement and the operation of any one of the rollbacks will bring one of the talons thereon into contact with either lug 15 or lug 16, depending on which direction the rollbacks are rotated, the engagement of the talons with the lugs moving stem 12 inwardly against the compression spring 20 and withdrawing latch bolt 11 from the keeper plate in the adjacent jamb of the door. The handle 28, which will be normally on the inside of the door, through the engagement of its shank 27 with rollback 19 is free to cause the withdrawal of latch 11 at all times, while handle 30 through the connection of its shank 29 with rollback 17 is free to cause the withdrawal of latch bolt 11 at all times except when the rollback 17 is dogged against movement by locking pin 69 upon being inserted into the openings 71 and 72 in tube 26 and shank 29, whereupon the handle 30 is locked against movement. In this condition of the lock mechanism the latch bolt 11 may only be actuated from the outside of the door by means of a proper key inserted into the cylinder lock mechanism.

Upon the insertion of a proper key in key plug 48, the breaks in the pin tumblers 52 are brought into alignment with the outer surface of key plug 48, whereupon the latter may be rotated by the key. The end of the usual key provided for this purpose is shown in dotted lines in Fig. 7, the end of the key being immediately beyond the innermost pin tumbler. Upon rotation of the key plug 48, and thereby its shank 55, the thimble 57 and square rod 58 are rotated, causing a rotary movement on the part of rollback 18 and the withdrawal of latch bolt 11.

So far in the description of my invention, I have been concerned with those features of the lock mechanism which enter into the normal operation of the lock. It is highly desirable, however, to provide a lock mechanism which may be readily disassembled to change the combination of the lock and for other purposes and I will now describe the features of my improved form of detachable lock which provide a suitable means to that end.

Referring again to the drawings, it will be seen that the key plug 48 is provided with a rectangular transverse slot 76 in which is slidably received a plunger 77 which is rectangular in cross section to fit slot 76 and which is constantly urged in one direction (downwardly, as viewed in Figs. 3, 5 and 7 of the drawings) by means of spring 78 secured on an upper part of shank 55 by means of screws 79. Part 35 of shank 29 and tube 26 are provided with transverse slots or openings 80 and 81, respectively, through which plunger 77 is forced by spring 78, the lower part of plunger 77 being provided with an abutment 82 which ordinarily rides on an inner surface 83 of cylindrical part 74, as shown in dotted lines in Fig. 5. Plunger 77 is free to rotate during the normal operation of key plug 48 in slots 80 and 81 to the extent that these

slots extend circumferentially of the parts in which they are formed but is normally held against movement in an axial direction by the transverse radially disposed walls of slot 81 in tube 26, is being understood that plunger 77 has a working fit between these walls. Tube 26 is provided with an axially extending slot 84 extending inwardly from the direction of handle 30 as far as and into slot 81, slot 84 being of a width but slightly greater than the width of abutment 82 (see Figs. 5, 6 and 7). As shown in Figs. 5 and 6, the slot 84 is offset with respect to the position occupied by abutment 82 when the pin tumbler parts are in alignment with one another, it being necessary to rotate key plug 48 and thereby the plunger 77 into the position shown in Fig. 6 of the drawings, in order to bring the abutment 82 into axial alignment with the slot 84. Plunger 77 is provided with an opening 85 in which the end 86 of a special key 87 may be received, the upper edge of key 87 being provided with camming surface 88 which engages the upper face 89 of opening 85. Key 86 is provided with suitable notches in order to properly align the pin tumblers to permit the rotation of the key plug.

When it is desired to detach the handle 30 and the parts carried thereby from door 9, the operation is as follows: Key 87 is inserted in the key opening 49, camming edge 88 of key end 86 entering the opening 85 and camming plunger 77 into the position shown in Figs. 3 and 5. The notches in the bit of the key bring the breaks in the pin tumblers into alignment with the surface of the key plug, whereupon the latter may be rotated into the position shown in Figs. 6 and 7 in which the abutment 82 is in alignment with the slot 84. The handle 30 may now be withdrawn from the lock case carrying with it the thimble 57 and shank part 35 which separates from part 36 owing to the tongue and groove connection therebetween. The screws 47 are now exposed and may be readily withdrawn from openings 46 by a suitable tool, whereupon the shank part 39 may be unscrewed from handle 30 and the cylinder lock 41 withdrawn. Upon changing the combination in cylinder lock 41 or effecting such other changes or corrections as may have required the dismounting of the lock, the cylinder lock 41 may be replaced in handle 30 and the shank part 39 and screws 47 reassembled, whereupon the handle 30 is ready to be reassembled on the lock.

A key 87 having notches thereon to properly align the pin tumblers is again inserted into the lock, the plunger 77 being again moved into the position shown in Fig. 3 of the drawings by the end of the key. The key plug is now rotated to bring abutment 82 into proper alignment with opening 84, whereupon the handle and associated mechanism may be moved axially into the position shown in Fig. 7, the tongues 37 again entering the grooves 38 and plunger 77 coming opposite slot 81 in tube 26. The key may be rotated into the position shown in Figs. 1 and 3, whereupon it may be withdrawn from the key plug, the plunger 77 thereupon being forced into the slot 81 and against surface 83 by spring 78.

From the foregoing description of my invention, it will be readily seen that I have provided a detachable lock mechanism in which the pin tumbler mechanism is no more complicated than in the usual lock and in which the secondary locking mechanism is relatively simple. With regard to the particular embodiment illustrated,

it will be seen that the mechanism presents exteriorly somewhat the same general appearance as the usual lock which is not provided with a detachable locking mechanism and that the parts of the mechanism are effectively concealed and are not where they may be tampered with. 5

While I have shown and described a preferred embodiment of my invention, it will be understood that the same is not to be limited to all the details shown but is capable of modification and variation within the spirit of the invention and the scope of the appended claims. 10

What I claim is:

1. In a lock, a lock mechanism, a handle for actuating said mechanism, and means for detachably connecting said handle to the lock mechanism, said means being key controlled, and permitting actuation of the lock mechanism by the handle when the latter is locked against detachment. 15

2. In a lock, a lock mechanism, a handle for actuating said mechanism, a shank on said handle, key controlled means for detachably locking said shank to the lock mechanism, while permitting rotation of the shank. 20

3. In a lock, a lock mechanism, a handle for actuating said mechanism, a tumbler mechanism within said handle, means for detachably connecting said handle to the lock mechanism, said means being controllable by a key received into the tumbler mechanism, and means permitting movement of the handle to actuate the lock mechanism when the handle is locked thereto. 25

4. In a lock, a lock mechanism, a handle for actuating said mechanism, a shank on said handle, tumbler mechanism in said handle, means for detachably connecting said shank to the lock mechanism, said means being controllable by a key received into the tumbler mechanism, and means permitting movement of the handle to 30 actuate the lock mechanism when the handle is locked thereto. 35

5. In a lock, a lock mechanism, a handle for actuating said mechanism, a tumbler mechanism in said handle, said mechanism including a key plug, means for detachably connecting said handle to the lock mechanism, a part of said means being carried by said key plug, said part being engageable by a key received in the key plug and movable by the key into handle detaching position. 45

6. In a lock, a lock mechanism, a handle for actuating the same, a shank on said handle, a tumbler mechanism mounted in said handle, said tumbler mechanism including a key plug, said key plug extending into the shank of the handle, and key controlled means carried by said key plug in said shank for detachably securing the latter to the lock mechanism, said means permitting actuation of the lock mechanism by the handle 50 when the latter is locked thereto. 60

7. In a lock, a lock mechanism, a handle for actuating the same, and key controlled means for detachably locking the latter to the lock mechanism, said means including a plunger, and an opening in a part of the lock mechanism in which the plunger is normally received, and means permitting actuation of the lock mechanism by the handle when the parts are in locked position. 65

8. In a lock, a lock mechanism, a handle mechanism for actuating said lock mechanism, and key controlled means to detachably lock said handle to the lock mechanism, said means including a plunger carried by the handle and an opening in a part of the lock mechanism in which the 70 75

- plunger is normally received, and means permitting actuation of the lock mechanism by the handle when the parts are in locking position.
9. In a lock, a lock mechanism, a handle mechanism for actuating said lock mechanism, and key controlled means to detachably secure said handle to the lock mechanism, while permitting movement of the handle relatively to the lock mechanism, said means including a plunger carried by one of the mechanisms normally received in an opening in the other mechanism.
10. In a lock, a lock mechanism, a handle mechanism for actuating said lock mechanism, a tumbler arrangement in said handle, means for detachably connecting said handle to the lock mechanism, said means including a plunger carried by one of said mechanisms, and an opening in the other of said mechanisms in which the plunger is normally received, said plunger being engageable by a key inserted into the tumbler arrangement to be moved into handle detaching position, the engagement between said plunger and opening permitting movement of the handle to actuate the lock mechanism.
11. In a lock, a lock mechanism, a handle for actuating said mechanism, a tumbler mechanism in said handle, normally inaccessible means for securing said tumbler mechanism in the handle, and key controlled means for rendering said securing means accessible to permit removal of the tumbler mechanism from the handle.
12. In a lock, a lock mechanism, a handle for actuating said mechanism, a tumbler mechanism secured within said handle, said securing means being inaccessible when the handle is mounted on said lock mechanism, and being accessible when the handle is removed therefrom, and key controlled means for detachably securing said handle to said lock mechanism.
13. In a lock, a tumbler mechanism, normally inaccessible means for securing said tumbler mechanism in said lock, and key controlled means for rendering said securing means accessible in order to dismount the tumbler mechanism from the lock.
14. In a lock, a lock mechanism, a handle for actuating said mechanism, said handle being made up out of a plurality of parts, means for securing said parts against relative movement, a tumbler mechanism in said handle, means on said lock mechanism normally covering the means for preventing relative movement between the handle parts, and key controlled means for permitting said handle to be moved away from the covering means.
15. In a lock, a lock mechanism, a tumbler mechanism controlling the operation of the lock mechanism, said tumbler mechanism including a key plug, means for detachably securing the tumbler mechanism to the lock mechanism, a part of said means being carried by the key plug and normally engaging the lock mechanism to hold the parts together, said part being engageable by a key inserted into the key plug and movable by the key into detaching position.
16. In a lock, a lock mechanism, a tumbler mechanism controlling the operation of the lock mechanism, said tumbler mechanism including a key plug, means for detachably securing the tumbler mechanism to the lock mechanism, said means including a plunger carried by the key plug normally engaging a part of the lock mechanism, said plunger being engageable by a key inserted into the key plug and movable by the key into detaching position.
17. In a lock, a lock mechanism, a handle for actuating the same, a cylinder lock carried in said handle, said cylinder lock including a key plug and a tumbler mechanism, and means for detachably securing the handle to the lock mechanism, said securing means including means carried by the cylinder lock and arranged to be engaged by a key to be brought into handle detaching position.
18. In a lock, a lock mechanism, a handle for actuating the same, a cylinder lock carried in said handle, said cylinder lock including a key plug and a tumbler mechanism, and means for detachably securing the handle to the lock mechanism, said securing means including means carried by the key plug and arranged to be engaged by a key to be brought into handle detaching position.
19. In a lock, a lock mechanism, a handle for actuating the same, a cylinder lock carried in said handle, said cylinder lock including a key plug and a tumbler mechanism, and means for detachably securing the handle to the lock mechanism, said securing means including a plunger carried by the key plug and arranged to be engaged by a key to be brought into handle detaching position.
20. In a lock, a lock mechanism, a handle for actuating the same, a cylinder lock carried in said handle, said cylinder lock including a key plug and a tumbler mechanism, and means for detachably securing the handle to the lock mechanism, said securing means including a plunger carried by the key plug and a groove in the lock mechanism in which the plunger is normally received, said plunger being adapted to be engaged by a key and moved in the groove into handle detaching position.
21. In a lock, a lock mechanism, a handle for actuating the same, a cylinder lock carried in said handle, said cylinder lock including a key plug and a tumbler mechanism, and means for detachably securing the handle to the lock mechanism, said securing means including a plunger carried by the key plug and a groove in the lock mechanism in which the plunger is normally received, said plunger being adapted to be engaged by a key and moved in the groove into handle detaching position, and a spring urging said plunger into said groove.
22. In a lock, a lock mechanism, a handle for actuating the same, a cylinder lock carried in said handle, said cylinder lock including a key plug and a tumbler mechanism and means for detachably securing the handle to the lock mechanism, said securing means including a plunger carried by the cylinder lock, a part of the lock mechanism being provided with a circumferential groove and an axial groove extending inwardly into said circumferential groove, said plunger being normally received in the circumferential groove and adapted to be engaged by a key inserted in the key plug to be partly withdrawn from the circumferential groove and rotated into a position opposite the axial groove.
23. In a lock, a lock mechanism, a handle for actuating the same, a cylinder lock carried in said handle, said cylinder lock including a key plug and a tumbler mechanism, and means for detachably securing the handle to the lock mechanism, said securing means including a plunger carried by the key plug, a part of the lock mechanism being provided with a circumferential groove and an axial groove extending inwardly into the circumferential groove, said plunger being normal-

ly received in the circumferential groove and adapted to be engaged by a key inserted in the key plug to be partly withdrawn from the circumferential groove and rotated into a position opposite the axial groove.

24. In a lock, a lock mechanism, a handle for actuating the same, a cylinder lock carried in said handle, said cylinder lock including a key plug and a tumbler mechanism, and means for detachably securing the handle to the lock mechanism, said securing means including a plunger carried by the key plug, a part of the lock mechanism being provided with a circumferential groove and an axial groove extending inwardly into the circumferential groove, said plunger being normally received in the circumferential groove and adapted to be engaged by a key inserted in the key plug to be partly withdrawn from the circumferential groove and rotated into a position opposite the axial groove, and resilient means normally urging said plunger into the circumferential groove.

25. In a lock, a bolt, a handle, and a plurality of selectively operable key operated means for retracting the bolt or detaching the handle.

26. In a lock, a bolt, a handle for retracting the bolt, and a plurality of selectively operable key operated means for retracting the bolt or detaching the handle.

30 27. In a door lock, a bolt, a case associated with the lock, and having locking mechanism housed therein and removable bodily therefrom, and a plurality of key operated means for selectively operating the bolt or detaching the case from the door.

40 28. In a lock, a lock mechanism, a handle for actuating the same, said handle being separable from and attachable to said mechanism by movement in a longitudinal direction, and key controlled means for securing said handle to the lock mechanism, said means permitting actuating movement of the handle when the latter is locked to the lock mechanism.

45 29. A lock having a frame, a knob having a shank attached to the frame, and a key-controlled member in engagement with said shank and frame for holding the shank from longitudinal movement for removal but permitting turning movement thereof, said key-controlled member being adapted to be retracted from said frame to permit the knob and shank to be removed.

50 30. A pin tumbler door lock comprising a removably securable section containing a key operated plug, an axially aligned retaining section containing a rollback operatively engageable by said plug, and key operated locking means adapted to normally secure said sections together.

60 31. A door lock comprising a removably securable section containing a key operated plug, a retaining section adapted to be secured to the door, said first named section having a part telescoped with said retaining section, key operated locking means adapted to secure said sections together, and said retaining section carrying a rollback operable by said plug.

65 32. A door lock comprising two sections, one of which is adapted to be secured to the door,

and a rollback movably carried by said one section, the other of said sections being removably securable to the first section and containing a key operated plug, means for operably connecting said plug to the rollback, and key operated means for securing the said sections together.

33. A door lock comprising two sections, one of which is adapted to be secured to the door, and a rollback movably carried by said one section, the other of said sections being removably securable to the first section and containing a key operated plug, means for operably connecting said plug to the rollback, and key operated means for securing the said sections together, said removably secured section having a part telescoped with the other section and a part abutting the end of the other section.

34. In a lock, a knob, a lock casing carried by said knob, a shank member removably secured to said knob and holding said lock casing within 20 said knob, a shank member to be secured to a door and cooperating with the shank member on said knob, a plug for said lock casing, and key operated means to be carried by said plug for locking said shank members together.

35. In a lock, a knob, a lock casing carried by said knob, a shank member removably secured to said knob, means to be carried by a door and cooperating with said shank member, and key operated means carried by said lock casing for holding said shank and means to be carried by a door against longitudinal displacement.

30 36. In a lock, a knob, a lock casing carried by said knob, a shank member in screw threaded engagement with said knob, a second shank member to be secured to a door, and key actuated means carried by said lock casing for detachably holding said shank members against longitudinal displacement.

35 37. In a lock, a knob comprising two separable parts, key actuatable means within said knob and partially projecting to the rear thereof, a rotatable hollow knob spindle, a mounting therefor independent of said knob, part of said key actuatable means normally connecting said knob to 45 said hollow spindle against longitudinal separation, a second key rotatable spindle passing through said hollow spindle, and rotatable by another part of said key actuatable means independently of said hollow spindle.

50 38. The combination with a hollow spindle of a lock, of a knob having a shank telescoping with said spindle and connected thereto for endwise removal therefrom, and a key-controlled spring-pressed latch member extending through said telescoping parts to secure them together, said knob being provided with a keyhole to receive a key to control said latch member.

55 39. The combination with a spindle in a lock, of a knob and knob shank secured to the spindle for endwise removal therefrom, a key-controlled compressible latch member extending radially through the spindle and knob shank to secure the knob against such endwise removal, and said knob being provided with a keyhole to receive a key to control said latch member.

JOHN H. SHAW.
